LIQUID FUEL FEED CONTROL

Thomas J. Stephens, New York, N. Y.

Original application August 3, 1940, Serial No. 350,927. Divided and this application April 24, 1943, Serial No. 484,390

2 Claims. (Cl. 236—8)

The present invention relates broadly to the burning of liquid fuel, such as fuel oil, and has reference specifically to the controlled feed of such fuel in response to heat demand in a zone of heat absorption.

This application is a divisional application of my copending application matured into U. S. Patent 2,337,006 issued Dec. 4, 1943.

The object of the invention is to provide a highly sensitive but positively reliable method and means for automatically increasing and/or decreasing the quantitative rate of fuel being continuously delivered into a zone of combustion, whereby the decrease will inversely correspond to a rise of temperature in the zone of heat consumption and the increase will inversely correspond to a fall of temperature in said zone, with the result that an almost exact temperature can be continuously maintained in the zone of heat consumption.

Means for carrying the invention into effect is illustratively exemplified in the accompanying drawing, in which the figure shows a control feed device applied to the baking chamber of an oven, which chamber may be considered as representative of any zone wherein heat is absorbed by a product or otherwise consumed or rendered latent.

Referring to the drawing, 62 and 63 denote two upright lengths of standard two-inch pipe which are united by means of a cross-fitting 64. The upper end of the lower pipe 63 is reduced by a bronze bushing 65 having an inside diameter of $1\frac{1}{2}$ inches. A length of light $1\frac{1}{2}$ inch diameter brass tube 66 is slidably disposed through the bushing within the pipes 62 and 63 and is of sufficient length to extend below the bushing 65 and above the level of an atomizing nozzle 67 under all conditions of service. The upper pipe 62 is loosely closed at its top by a cap or other appropriate fitting 68 having a concentric opening 69 at its upper end. A $\frac{3}{8}$ inch rod 70 passes slidably through the opening 69 in said cap and is concentrically fixed at its lower end to the upper end of said brass tube 66. The brass tube and rod assembly are slidably disposed relative to the pipe assembly 62—63 in a manner which allows the rod and tube to be actuated by gravity. A radial arm 71 is attached to the pipe 62 by being clamped thereto near its upper end. At the outer end of said arm an upwardly extending post 72 is fixed, the upper end of which pivotally supports one end of a movable lever 73. Intermediately of the post and the pipe and on the arm a pressure operated bellows 74 is located, the

bellows used being preferably of the known "Sylphon" type which is covered by a protective housing 75 having a guiding tube 76 fitted concentrically in its top. A rod 77 is slidably fitted in the tube with its lower end resting on the head of the bellows and engages the said lever 73 by means of a slideable connection 78. The other end of the lever 73 is pivotally and slidably connected to said rod 70 in such manner that upward or downward movement of the lever will respectively elevate and lower the tube 66. Openings 79 are provided in the wall of the brass tube 66 at an elevation below the level of the burner nozzle 67 when the tube is in its maximum elevated position. A pump 80 for delivering fuel oil from a source of supply is connected to a pipe 81 which is connected to one of the lateral openings of said cross-fitting 64. The opposite lateral opening of said cross is connected to a pipe 82 which connects with the fuel atomizing nozzle 67.

As the pump is operated, fuel oil will flow into the cross-fitting 64 and fill the annular space above the bushing 65 between the pipe 62 and the brass tube 66 until its level reaches the openings 79 in the tube. The oil then flows through said openings and downwardly through the brass tube 66 and pipe 63 to a return pipe connection 83 through which it returns to the source of fuel supply from which it was drawn by the pump. In this manner a continuous supply of fuel oil in excess of that required by the operation is circulated. The fuel oil in the lateral branch 82 which supplies the atomizer 67 will stand at the same level as in the annular space in the pipe 62. Thus, by elevating or lowering the slideable tube 66, the oil supply level, below the atomizer in the pipe 82 is respectively elevated or lowered. The atomizer nozzle 67 is of the aspirating or Venturi type and is operated by a supply of steam or compressed air maintained at constant pressure, and delivered to the nozzle through a tube 84. Under constant conditions of aspiration the quantity of fuel projected from the nozzle will vary on an inverse ratio to the distance through which the liquid is raised by the aspirating influence.

The said "Sylphon" bellows 75 mounted on the carrying arm 71 is provided with a gasket to establish a pressure tight seal except for a minute bleed opening 85 in its base. The pressure tight tube 84 communicates between the interior of the bellows and the supply of steam or compressed air which comprises the aspirating or atomizing agent for the fuel. An electrically

operated valve 86, normally open, is placed in said latter tube. An electric switch normally closed is operative by a heat sensitive instrument 87 which is located in the baking chamber A of the oven, and is connected through an electric circuit 88 to said electrically operated valve 86. When temperature in the baking chamber rises above that at which the instrument is set, the electric switch is opened by the heat sensitive instrument 87 to open said electric circuit 88, and close said electrically operated valve 86, thereby allowing pressure to be exhausted from the interior of the bellows 74 through said bleed opening 85. The lever arm 73 is provided with a weight 89 which, together with the weight of the rod 70 and the tube 66 is sufficient to cause the tube 66 to descend as pressure is exhausted from the bellows 74, thus lowering the level of the liquid fuel in the supply pipe 82 to the atomizer, resulting in diminishing of fuel feed to the zone of combustion.

Inasmuch as the lifting power of the lever 73 is applied intermediately of its two ends and one end is pivotally fixed, it is obvious that the range of movement of the other end will be limited by the position of the lifting element 78. The housing 75 of the bellows 74 is slidably mounted on the arm 71 in a manner such that it can be shifted along the arm 71 and fixed thereto in any position between a point near the fulcrum of the lever 73 and a point near its opposite end. The expansion of the bellows 74 is limited by its contact with the top of the housing 75, thus defining the maximum elevation of the rod 70. The descent of the rod 70 is limited to that position at which the lower end of the slidable connection 78 rests upon the upper end of the tube 76. Accordingly, by adjusting the position of the housing 75 together with its assembled parts 76, 77 and 78, the differential between the low level and the high level of the opening 79 can be varied from a very considerable differential to a very slight one to meet the requirements of a wide variety of operations. For example, in an operation in which heat consumption proceeds at a uniform rate a slight differential in the fuel levels resulting in a slight variation between low fire and high fire is desirable; on the other hand, in the case of an operation in which heat consumption is considerable for a short period and inconsiderable during a succeeding period, a wider range between high fire and low fire is desirable in order to cover both conditions economically. In all cases the high fire should be such as to generate a quantity of heat slightly in excess of the rate of

heat consumption and the low fire should be such as to generate a quantity of heat slightly less than the rate of heat consumption. The high fire will correspond to the high level and the low fire to the low level of the fuel in the stand pipe 62.

It is to be noted that the present invention is useful only in combination with aspirating atomizers. The term "aspirating atomizers" designates that type of atomizing nozzle or device through which gas, such for example as compressed air or steam under pressure, when released through the nozzle, is capable of elevating liquid from a level beneath that of the nozzle and projecting it, in finely divided form, suspended in the jet issuing from the nozzle. A synonym for aspirating atomizer or nozzle is "Venturi tube or Venturi nozzle" or any combination employing the "Venturi" principle.

I claim:

1. In a heat generating and consuming apparatus, the combination of a combustion chamber, a stationary aspirating nozzle disposed to deliver atomized liquid fuel into said chamber, means for passing through said nozzle an aspirating agent maintained at uniform pressure, a rise pipe communicating between said nozzle and a source of fuel supply, means for supplying fuel under pressure to said pipe, and an overflow mechanism arranged for cooperation with said pipe to maintain the fuel level in the latter below that of the nozzle and including means for automatically varying the vertical distance between the level of said nozzle and the overflow level and, thus, the level of the fuel in said pipe in response to the varying demand upon the combustion chamber for heat between a predetermined high level and a predetermined low level, both below the level of said nozzle.

2. In a heat generating and consuming apparatus the combination of a combustion chamber, a stationary aspirating nozzle disposed to deliver atomized liquid fuel into said chamber, means for passing through said nozzle an aspirating agent maintained at uniform pressure, a rise pipe disposed between said nozzle and a source of fuel supply and in communication therewith, means for supplying fuel under pressure to said pipe and an overflow mechanism arranged for cooperation with said pipe to maintain the fuel level in the latter below that of the nozzle and including means for automatically varying the overflow level and thus varying the level of the fuel in said pipe in response to the varying demand upon the combustion chamber for heat.

THOMAS J. STEPHENS.
